UNITED STATES PATENT OFFICE.

WILLIAM BECK, OF TULSA, OKLAHOMA.

EXPLOSIVE CONTAINER.

Application filed June 18, 1921. Serial No. 478,764.

To all whom it may concern:

Be it known that I, WILLIAM BECK, a citizen of the United States, and a resident of Tulsa, in the county of Tulsa and State of Oklahoma, have invented certain new and useful Improvements in Explosive Containers, of which the following is a specification.

This invention relates to explosive containers especially adapted for use in oil and gas wells.

The nitroglycerin containers employed in oil and gas wells are generally of only a single thickness and the heat generated by the contact of the container with the wall of the casing is transmitted through the wall of the container with the result that the explosive contained therein is ignited. Also, the containers are in many cases slightly leaky and thereby allow a small quantity of explosive to escape and possibly cause premature explosion of the main body of explosive.

A further difficulty encountered is the fact that burs and the like on the inner wall of the casing frequently puncture the explosive container and thereby permit the explosive contained therein to escape.

It is therefore, the aim of this invention to provide an explosive container consisting of inner and outer shells, the outer shell forming a means for protecting the inner shell from frictional contact with the wall of the casing and also to prevent the inner shell from being punctured.

By the use of a double shell container any explosive which might escape from the inner shell will be confined within the outer shell and thereby prevented from causing premature explosion of the main body of explosive.

Other objects and advantages will be apparent during the course of the following description.

In the accompanying drawing forming a part of this application and in which like numerals are employed to designate like parts throughout the same,

Figure 1 is a side elevation of the container in use.

Figure 2 is a central vertical sectional view through the same.

Figure 3 is a sectional view taken on line 3-3 of Figure 2.

In the drawing the numeral 5 generally designates the improved nitroglycerin con-

tainer which is adapted to be lowered into a well casing 6 by means of a cable 7 or other suitable means.

The improved container comprises an inner shell 8 adapted for the reception of a quantity of nitroglycerin 9 or other explosive. The nitroglycerin is introduced into the inner shell 8 by means of a funnel shaped member 10 extended downwardly into the body of the shell. The inner shell 8 is formed adjacent its lower end with an inwardly directed rib 12 to which a bottom wall 13 is connected by means of a flange 14.

An outer shell 16 receives the inner shell 10 and is arranged in spaced relation to the same to form an annular water chamber or jacket 17 into which water may be introduced by means of an opening 18. As illustrated in Figure 2, the opening 18 is arranged above the level of the explosive and above the plane of the outlet end of the funnel shaped member 10 so that the water level will be above the explosive level.

Also, the cone shaped ends 20 and 21 of the inner and outer shells respectively define a cone shaped water jacket 23 at the forward end of the annular water jacket 17. It is thus apparent that the nitroglycerin contained in the inner shell is surrounded by a body of water which maintains the explosive in a cool condition when the container is being lowered into a well.

Should the inner shell develop a leak, the escaping nitroglycerin will be confined in the jacket 17 so that it is prevented from coming in contact with the wall of the casing and possibly causing a premature explosion in the well casing.

A further function of the outer shell 16 resides in the fact that it protects the inner explosive containing shell from splinters and projections in the casing and thereby prevents the puncturing of the inner shell.

Should the device come in frictional contact with the wall of the casing, the heat generated will not be transmitted to the explosive but will be effectively absorbed by the water contained in the jackets 17 and 23. By the use of this invention, the explosive may be lowered to the desired distance in the well casing without the possibility of a premature explosion and a resulting loss of time and money. The container may be made in a variety of sizes and may be manufactured at an extremely low cost.

I claim:—

1. An explosive container for wells comprising inner and outer spaced shells defining a jacket adapted for the reception of 5 a protecting and heat absorbing medium, the inner shell being adapted for the reception of a fluent explosive and having its upper end formed with an inlet opening, said jacket being extended about said inner shell to receive the leakage from the same.
2. An explosive container for oil wells comprising an inner shell adapted for the reception of a fluent explosive, and an outer protecting shell completely surrounding the 15 sides and forward end of the inner shell in spaced relation to the same and defining a water chamber, said chamber being adapted for the reception of the leakage of the explosive.
3. An explosive container for oil wells comprising an inner shell adapted for the reception of a fluent explosive, an outer protecting shell surrounding the inner shell in spaced relation to the same and cooperating 25 with the inner shell in forming a water chamber, said outer shell being provided adjacent its upper end with a water inlet opening, and inner and outer spaced cone shaped members arranged at the for-
- ward ends of said shells and defining a cone 30 shaped water chamber communicating with said first named water chamber, said chambers being adapted for the reception of the leakage from said inner shell.
4. A nitroglycerin container for use in 35 oil wells comprising an inner cylindrical shell adapted for the reception of nitroglycerin and having a funnel shaped inlet portion, an outer cylindrical shell surrounding the inner shell in spaced relation to the same thereby forming an annular protecting chamber, said outer shell being provided above the outlet end of said inlet portion with a water inlet opening, the lower end wall of said inner shell being spaced from 40 the forward end of said protecting chamber whereby the water extends for a substantial distance beyond the body of nitroglycerin contained within the inner shell, and inner and outer spaced cone shaped members secured to the forward ends of said shells and defining a cone shaped water chamber in communication with said protecting chamber, said outer shell constituting a protector for the nitroglycerin container, and 45 also constituting a receiver for the leakage of the nitroglycerin.

WILLIAM BECK.
